W. P. HARLAN.

FLUME GATE,

APPLICATION FILED APR. 1, 1918.

1,298,936.

Patented Apr. 1, 1919.

UNITED STATES PATENT OFFICE.

WILSON POLK HARLAN, OF YUMA, ARIZONA.

FLUME-GATE.

1,298,936.

Specification of Letters Patent.

Patented Apr. 1, 1919.

Application filed April 1, 1918. Serial No. 226,027.

To all whom it may concern:

Be it known that I, WILSON POLK HARLAN, a citizen of the United States, residing at Yuma, in the county of Yuma and State of Arizona, have invented certain new and useful Improvements in Flume-Gates, of which the following is a specification, reference being had to the accompanying drawings.

10 This invention relates to irrigation, and particularly to the flume gates of irrigating ditches.

The object of the invention is to improve the details of that form of flume gate in 15 which a concrete head is used and a metallic slide or gate insertible into the head or removable therefrom.

Specifically speaking, one of the objects of the invention is to provide a slide or 20 gate with a handle which, when the slide is in place, has its upper end flush with the top of the body of the gate, thus preventing stock from rubbing against and bending the handle and bending the slide, and in this 25 connection to form this handle of strap iron so bent that it will form a convenient grip for the operator.

A further object is to so form the gate 30 head or body that a guide is provided for the slide, this guide opening downward from the top of the body and easily guiding the slide into place in the guide grooves of the body, so that the operator may readily put the gate in place if the head be submerged. 35 or at night.

A further object is to so form the sheet 40 metal slide that a double folded rim is provided which prevents the bending of the top portion of the slide and causes the slide to fit the concrete head properly, preventing leakage of water past the slide.

Still another object is to provide a transversely extending recess or trough extending across the face of the head which will receive the bottom of the slide and which is so formed as to allow silt to collect in this trough, thus making a water tight connection between the head and the slide at the bottom thereof.

50 Other objects will appear in the course of the following description.

My invention is illustrated in the accompanying drawings, wherein:—

Figure 1 is a face view partly broken away of my improved flume gate; 55

Fig. 2 is a vertical sectional view through the gate;

Fig. 3 is a horizontal sectional view; and

Fig. 4 is a fragmentary perspective view of a corner of the gate body. 60

Referring to these drawings, 10 designates the body of the flume which is provided with the head 11. The body is shown as circular in cross section and the head 11 as rectangular and as projecting in all directions beyond the periphery of the circular portion 10. This head is slightly inclined downward and forward with relation to the axis of the body 10 and has a downwardly and forwardly inclined recessed face 12, the 70 side walls of this recessed face being undercut as at 13. Extending transversely below the recessed face 12 is a recess 14, the outer wall of which is upwardly and outwardly beveled or rounded as illustrated more particularly in Fig. 2. The lateral grooves 13 are also outwardly and forwardly beveled as illustrated in Fig. 3. At its upper end the head 11 is cut away or otherwise formed to provide a relatively deep transversely extending recess 15, having downwardly beveled side walls 16 intersecting the outer ends of the grooves 13 and defined at its lower end by a shoulder 17, this shoulder being located at the upper end of the recessed face 80 of the head. 75

Sliding in the grooves 13 is the gate or slide 18, which is made of sheet metal. The lateral margins of this sheet metal are bent outward and forward as at 19 and fit the outer 90 walls of the grooves 13 and resiliently bear against the faces of these walls. At its upper end, the gate or slide 18 is angularly flanged as at 20 and then rebent upon itself as at 21. The flange 20 rests upon the shoulder 17 and the return bend given to this flange stiffens the top of the slide and prevents the slide from becoming bent, thus causing the slide to fit against the shoulder 17 more efficiently than it otherwise would do. 95

Attached to the face of this slide 18 is a handle composed of a strip 22 of strap iron bent into U form, the legs of the strip being riveted to the slide and the strip being given a quarter turn at its middle so that the upper portion of the handle 23 is disposed in 100 105

a horizontal plane and at right angles to the plane of the legs 22. The middle portion of the handle extends above the upper end of the gate but the handle is of such length that when the slide is seated in the bottom of the groove 14, the cross bar 23 of the handle will not project above the upper face of the body 11. In other words, the handle will be disposed within the recess 15. Thus the top of the handle is flush with the top of the head which prevents stock from rubbing against or bending the handle or displacing the slide. As before noted, the groove 14 extends continuously across the lower end of the inclined face of the head which forms the seat for the slide 18 and there are no breaks or openings in the front wall of the groove 14. Hence silt will collect in this groove or trough and the lower end of the slide will extend into this silt thus making a water tight connection between the lower end of the slide and the head.

It will be noted that the inclined walls 16 extend downward to the outer corners of the guide grooves 13 so that in inserting the gate proper or slide, these laterally inclined surfaces 16 will guide the lower end of the gate to the grooves, thus making it very easy to insert the gate or slide when the head is submerged in water or at night. The strap iron handle, which is slightly channeled in cross section so as to make it rigid stiffens the sheet metal slide or gate so that it will

not become bent or deformed under water pressure or in service.

While I have illustrated the body 10 as comprising a tubular portion with a rectangular head at one end, it will be understood that this rectangular head might form part of a rectangular box with other flumes leading therefrom as is common in constructions of this character and that I do not wish to limit myself to any particular constructions of the head, except as set forth in the appended claim.

Having described my invention, what I claim is:

A flume gate comprising a concrete body having a passage for the flow of water, vertical grooves on opposite sides of the passage and forming a slideway, and a groove below the passage and connecting the lower ends of the vertical grooves and forming a sand pocket across the bottom of the slideway; a gate mounted to be moved up and down in the slideway and to extend into the sand pocket; and means at the top of the gate for limiting the downward movement of the gate so as to protect the sand pocket from the weight of the gate.

In testimony whereof I hereunto affix my signature in the presence of two witnesses.

WILSON POLK HARLAN.

Witnesses:

WADE H. HOOD,
FRANK JOHNSON.
